Patented Jan. 20, 1920.

UNITED STATES PATENT OFFICE.

KNUD KNUDSEN, OF PLAINVILLE, CONNECTICUT, ASSIGNOR TO THE TRUMBULL ELECTRIC MANUFACTURING COMPANY, OF PLAINVILLE, CONNECTICUT, A CORPORATION OF CONNECTICUT.

ELECTRIC SWITCH.

1,328,798.

Specification of Letters Patent.

Patented Jan. 20, 1920.

Application filed November 11, 1918. Serial No. 262,039.

To all whom it may concern:

Be it known that I, KNUD KNUDSEN, a subject of the King of Denmark, having signified intention of becoming a citizen of the 5 United States and taken out first papers and applied for second, residing at Plainville, Connecticut, have invented a new and useful Electric Switch, of which the following is a specification.

10 My present invention is a no-voltage or low voltage release for switch mechanism.

The objects of the invention are to provide simple and effective mechanism of this nature, a special aim being to provide trip 15 mechanism which will be capable of securely holding the switch and which at the same time will be sensitive in its action and dependable in operation.

Another object is to provide trip mechanism of this character which can be operated when desired, manually, as well as automatically.

The invention may be briefly described as consisting of a latch member, usually in 25 the form of a pivoted lever, for holding the movable switch element in one position and a trip member for the latch, also usually in the form of a lever and pivoted at right angles to the latch lever, and controlled by 30 a no-voltage or low voltage solenoid.

Manual control of the latch is obtained by providing the core of the no-voltage solenoid with a finger button by means of which the same may be actuated irrespective of the action of the solenoid winding.

Other features of the invention will appear as the specification proceeds.

The accompanying drawing is an illustration of the invention as embodied in a practical and commercial form. It will be understood however, that such illustration is primarily made for the purpose of disclosure and that the invention is not limited to the form shown, but may be modified as required or found desirable without departure 45 from the spirit and scope of the invention.

In said drawing:

Figure 1, is a side view of the invention as applied to a form of so-called "safety" 50 or inclosed switch, only a fragment of the switch casing appearing in this view.

Fig. 2, is a plan view of these parts with part of the casing of the latch mechanism

broken away as on the plane of the line 2—2 of Fig. 1.

Fig. 3, is a vertical sectional view taken substantially on the plane of the line 3—3 of Fig. 2.

Fig. 4, is another sectional view taken on the plane at right angles to Fig. 3 and substantially on the line 4—4 of Fig. 2.

As the invention primarily resides in the latch mechanism of the switch, only so much of the switch is shown as is necessary to bring out the relation of the latch mechanism thereto. The movable element of the switch consists, in this disclosure, of a series of pivoted switch blades 5 connected through suitable connections 6 with a pivoted switch handle 7, the whole forming what may be 70 considered the movable element of the switch. The switch handle is pivotally supported on the side wall of the switch box or casing 8 which provides a relatively stationary support for the same and for the 75 latch mechanism now to be described.

9 designates the latch member consisting in the present disclosure of a lever pivoted intermediate its ends at 10 and provided at its forward end with a hook 11 for engagement over an outstanding lug or pin 12 on the switch handle 7. Near the opposite free end this latch lever is acted on by a spring 13 which exerts its tension to bias the latch in a direction to release the switch 85 handle.

The latch is secured in holding engagement with the movable switch element by means of a trip lever, here shown in the form of a bell crank having an upstanding 90 arm 14 disposed in the path of yielding or releasing movement of the rear end of the latch lever and an angular or laterally outstanding arm 15. This trip lever is shown pivotally supported at 16 and as provided 95 on the upstanding arm 14 thereof with a stop shoulder 17 designed to be engaged by the rearwardly extended end of the latch lever 9. The trip lever is biased toward the latch lever in the illustration, by 100 means of a spring 18.

The pivot 16 for the trip lever, it will be noted, is disposed substantially at right angles to the pivot 10 for the latch lever so that said trip lever can swing across the 105 path of the releasing movement of the latch

lever. Furthermore, the pivot 16 is disposed substantially in line with or directly beneath the end of the latch lever so that when the trip lever stands in the path of the tail of the latch lever it will form a firm stop positively holding said latch lever against any releasing movement. On the other hand, the trip lever is peculiarly sensitive in that but a very slight effort on the 10 outstanding lever arm 15 is necessary to rock the trip out of holding engagement with the latch lever. Only a very slight effort therefore, is required to trip the latch lever and the effort necessary is further reduced by making one of the levers of a non-corrosive metal such as brass. At the present time I prefer to make the trip lever out of brass and the latch lever out of any suitable metal such as steel. This relation of the 20 two metals enables the trip to slip easily from engagement with the latch lever and prevents any "sticking" of the parts.

The no-voltage or low voltage release magnet is shown in the present disclosure as 25 a solenoid consisting of a hollow coil 19, and a magnetic core 20 working therein and "floated" or sustained thereby when the coil is properly energized. This core has a direct connection with the trip lever in the 30 construction illustrated through the medium of an outstanding shoulder or flange 21 mounted on the upper end of the solenoid core stem 22 and overlying the laterally outstanding arm 15 of the trip lever. The 35 weight of the solenoid core is sufficient for the same, when released by the solenoid, to rock the trip lever out of engagement with the latch lever and thus permit the latch to free the movable switch element.

40 The movable element of the switch is influenced or biased in a switch opening direction in the present disclosure by means of a spring 28. In closing the switch this spring is placed under tension and is therefore put in condition to open the switch as 45 soon as the latch is released. The hook 11 of the latch is usually beveled substantially as indicated on its outer end so that in the closing movement of the switch the pin 50 12 on the switch handle will ride over this bevel, rocking the latch in such a way as to permit the hook to snap over and into holding engagement with the pin 12. Upon closing the switch the solenoid winding becomes energized, lifting the core up about 55 to the position shown wherein the weight of the core is removed from the trip lever and the trip lever thereupon rocks into the holding position shown in Fig. 4. The switch 60 then remains latched in its circuit-closed position until the magnet becomes deenergized to such an extent as to drop the core into engagement with the trip lever, whereupon said lever will release the latch and permit 65 the switch to be snapped open.

In order that the switch may be tripped by hand whenever desired I have shown a push button 24 provided on the upper end of the core stem 22 in position to be easily engaged by the thumb or finger. The solenoid and other parts of the latch mechanism are preferably inclosed within a protective casing 25. This casing is usually extended to cover the sides of the core stem as indicated in Figs. 1, 2, and 4 so as to guard 75 against accidental depression of the core but at one side this guard may be cut down or recessed as indicated at 26 so as to provide ready access for the finger of the operator. At the lower end the protective casing may 80 be left open as indicated at 27 so as to provide access to the lower end of the core and therefore enable the core to be lifted by hand whenever desired.

I claim:—

1. In an electric switch, the combination with the movable element of the switch mechanism, of a latch lever pivoted intermediate its ends and adapted to engage the movable switch element at one end to hold the same in a predetermined position, a trip lever pivoted on an axis substantially in line with the opposite end of the latch lever and adapted to engage said end of the latch lever to hold the same with the opposite end in holding engagement with the movable element of the switch mechanism, and means for actuating said trip lever to free the same from holding engagement with the one end of the latch lever to thereby permit the latch lever to swing on its pivot so as to free the opposite end of said lever from holding engagement with the movable switch element.

2. A switch construction comprising, a 105 box, switch mechanism mounted therein, an operating handle on the exterior of said box, a latch member for said handle, a trip lever for said latch member, a solenoid having a movable core adapted to coact with said trip member, an auxiliary casing exterior to the box and surrounding said solenoid and its core and said trip lever and having an opening for access to said core, and an exposed button for manually operating said trip lever.

3. In an electric switch, the combination with the movable element of the switch mechanism, of a latch for securing said switch element in one position and yieldable in a direction to release the switch element, a trip standing in the path of releasing movement of the latch and movable out of said position to release the latch, a magnet controlling said trip lever, said magnet comprising a solenoid and a core adapted to be supported thereby, said core having a connection with the trip and provided with a button by means of which the same may be manually operated.

4. A switch construction comprising, a box, switch mechanism therein, an operating handle exterior to the box, a spring pressed pivoted latch for holding said handle in one position, a spring pressed pivoted trip for engaging said latch and an electro-magnetically operated member for engaging said trip, an auxiliary casing exterior to said box and surrounding said trip, a part of 10 said latch, and said electro-magnetically operated member.
5. In an electric switch, the combination with a movable switch element normally biased to the open circuit position, a pivoted 15 latch lever for securing said switch element in circuit closed position, a pivoted trip lever for securing the latch lever in its holding position, a solenoid coil, a core sustained thereby when said coil is energized, and an 20 arm on the trip lever projecting in the path of falling movement of the solenoid core, the falling energy of said core being sufficient to operate said trip lever.
6. In an electric switch of the character 25 described, the combination with the movable element of the switch mechanism, of latch mechanism for holding the same in a pre-determined position, a solenoid comprising a winding and a core normally sustained 30 thereby, connections between said core and latch mechanism whereby the solenoid will control the latch mechanism and an exposed push button carried by the solenoid core for enabling manual operation of the same.
- 35 7. In an electric switch of the character described, the combination with the movable element of the switch mechanism, of latch mechanism for holding the same in a pre-determined position, a solenoid comprising 40 a winding and a core normally sustained thereby, connections between said core and
- latch mechanism whereby the solenoid will control the latch mechanism, an exposed push button carried by the solenoid core for enabling manual operation of the same, and 45 a casing inclosing the connections and the push button aforesaid and provided with a recess for access of an operating member to the push button.
8. In an electric switch, the combination 50 with a movable switch element normally biased to the open-circuit position, a pivoted latch lever for securing said switch element in circuit-closed position, a trip lever pivoted substantially at right angles to the pivotal mounting of the latch lever for securing the latch lever in its holding position, a solenoid coil, a core sustained thereby, an angular arm outstanding from the trip lever and disposed in the path of movement of the 55 solenoid core so as to be actuated thereby upon the fall of said core, said core having a push button on the upper end thereof whereby the same may be manually depressed to trip the latch and the lower end 60 of the core being exposed to enable the core being manually lifted when the switch is being closed.
9. In an electric switch, the combination 65 with a movable switch element, of a pivoted latch lever for securing said switch element in one position, a trip lever pivoted on an axis substantially at right angles to the pivotal axis of the latch lever for securing the latter in its holding position, one of said 70 levers being constructed of non-corrosive metal to enable the trip lever sliding freely from engagement with the latch lever and a release magnet controlling movement of the trip lever.
- 75

KNUD KNUDSEN.
